DESIGN FOR A CHILD'S WHEELED TOY

Merrell M. Johnson, Iowa City, Iowa

Application June 16, 1936, Serial No. 63,332

Term of patent 3½ years

To all whom it may concern:

Be it known that I, Merrell M. Johnson, a citizen of the United States of America, residing at Iowa City, in the county of Johnson and State of Iowa, have invented a new, original, and ornamental Design for a Child's Wheeled Toy, of which the following is a specification, reference being had to the accompanying drawing, forming part thereof.

wheeled toy, showing my new design.

I claim:—

The ornamental design for a child's wheeled toy, as shown.

MERRELL M. JOHNSON.
